UNITED STATES PATENT OFFICE.

HENRY W. ALLPORT, OF THE UNITED STATES ARMY.

ASEPTIC PACKAGE FOR SURGICAL DRESSINGS.

1,356,331.

Specification of Letters Patent. Patented Oct. 19, 1920.

Application filed January 24, 1919. Serial No. 272,940.

(FILED UNDER THE ACT OF MARCH 3, 1883, 22 STAT. L., 625.)

To all whom it may concern:

Be it known that I, HENRY W. ALLPORT, captain, U. S. Army, a citizen of the United States, stationed at Washington, D. C., have invented an Improvement in Aseptic Packages for Surgical Dressings, of which the following is a specification.

The invention described herein may be used by the Government, or any of its officers or employees in prosecution of work for the Government, or by any other person in the United States, without payment of any royalty thereon.

My invention relates to an improvement in aseptic packages for surgical dressings, one object being the provision of a package which will protect and keep the dressing clean and sanitary while instantly accessible when desired, and which will accommodate rolls of dressing of different widths.

Another object of my invention is the provision of a device of the character described and for the purpose stated, which will contain the dressing in proper condition, and which will act after the manner of a follower or brake to hold the package of dressing at all times in proper position for use, as the package is unwound.

Another object of my invention is the construction of an aseptic package which can be manufactured at such a price as to make its use highly desirable, which will operate in an efficient manner under all conditions and which, from every point of view, will prove entirely practical.

With these and other inherent objects in view, the invention broadly stated consists of an aseptic package for surgical dressings, comprising a box or container, a follower or brake which bears upon the roll of dressing and a guard or protecting flap formed integral with said follower or brake.

The invention further consists of an aseptic package for surgical dressings, embodying novel details of construction, combination and arrangement of parts for service, substantially as shown, described and particularly pointed out in the claims, it being of course understood that any change may be made in the construction of the invention, which comes within the scope of such claims.

Figure 1 is a plan view of the sheet or blank from which the package is formed,

showing the manner of scoring the blank to 55 produce its component parts or sections;

Fig. 2 is a perspective view of the complete package with the roll of bandage therein the end of the package being removed to show the relative location of the 60 bandage and container; and

Fig. 3 is a transverse sectional view particularly illustrating the relation of the roll of bandage to the container, and the bearing of the follower against said roll of bandage which forms one of the most important features of my invention.

In the manufacture of the aseptic package, any desired or preferred material may be used, and in such manufacture a sheet or 70 blank is provided and is cut to provide the bottom 1, the sides 2 and 3, the flaps 4 and 5, which when the box is assembled, form the ends thereof, the top 6 formed with the lock tongue 7, and the section 8 which is 75 scored or marked centrally at 9 and is adapted to be folded or bent upon itself to form a follower 10, said section being formed with a flap 11, which, when the parts are in position, provides a guard 80 adapted to rest upon the roll 12 of the bandage, and provides a passage or slit 13 through which the end 14 of said roll of bandage projects to permit such roll to be 85 unwound as found necessary.

In using my improved package, the roll of bandage is placed in the box or container and the end projects through the passage between the guard and one of the sides of the box, permitting the person to 90 grasp the projecting end of the bandage and unwind the necessary amount, the guard and follower which is formed by bending the material upon itself to form a doubled wall or bellows-like portion which 95 has sufficient elasticity to cause expansion of said follower to effect the retaining the roll in proper position, and should any soil from the hand be found upon projecting end, the portion of material thus soiled 100 can be readily removed by the use of shears. Thus a clean strip of bandage of the desired length is provided, while the balance or unused portion of such roll is 105 retained in the box or container in a clean and sanitary condition for further use.

From this construction it will be evident that the box forms a container which per-

mits instant access to the roll of bandage and permits the withdrawal of any desired amount from such roll, and at the same time entirely prevents any outside contact of the 5 hands of the user, as well as any entrance of dirt or foreign matter into the container.

It will also be apparent that the package, when closed, entirely conceals and protects the roll of bandage, but permits instant access to said package when found necessary, 10 and that rolls of bandage of various widths may be used, and that the guard bears firmly upon the roll to retain it in proper position, while the follower formed with 15 said guard bears upon the roll as it diminishes in size, and thus holds such roll in proper position to permit the unwinding of the necessary amount.

I claim:—

- 20 1. An aseptic package for surgical dressings consisting of a blank forming the bottom, sides, ends and top, and an auxiliary section formed with one of the sides, and scored to provide a follower to bear upon 25 a roll of bandage and a guard to protect and retain said roll of bandage in proper position, said follower being formed by bending the material upon itself to form an expandible member which extends from 30 the top of the receptacle nearly to the bottom thereof to cause the follower and guard to bear upon the roll of bandage within the container.
2. An aseptic package for surgical dressings consisting of a container, a section formed integral with one side of said container and provided with a double portion forming a follower, and a flap providing a guard or protector, and a top section 35 formed with a tongue, adapted to close and protect the contents in its entirety, said follower being formed by bending the material upon itself to form an expandible member which extends from the top of the receptacle nearly to the bottom thereof to cause the follower and guard to bear upon the roll of bandage within the container.
3. An aseptic package for surgical dressings consisting of a box or container, a 40 section formed integral with one of the sides of said container, and consisting of two parts, one bent upon itself to form a follower, and the other part forming a 45 receptacle nearly to the bottom thereof to cause the follower and guard to bear upon the roll of bandage within the container.

- 50 4. An aseptic package for surgical dressings comprising a body having a top section, and a protective guard carried by said body for the contents thereof, when the top section is open, and having a follower for the contents wholly within the body and working transversely thereof, said follower being formed by bending the material upon itself to form an expandible member which extends from the top of the receptacle nearly to the bottom thereof to cause the follower and guard to bear upon the roll of bandage within the container.

5. In the package or container of the character described, the combination with the containing portion of said box or container of a combined follower and guard formed integral with one side of said box or container, and a protecting cover formed integral with the opposite sides of said box or container, said follower being formed by bending the material upon itself to form an expandible member which extends from the top of the receptacle nearly to the bottom thereof to cause the follower and guard to bear upon the roll of bandage within the container.

6. A box or container of the character and for the purposes stated, having a portion constructed to provide a follower to bear upon the roll of bandage, as it is unwound, and a guard for protecting such roll of bandage under all conditions to prevent access of foreign matter to said roll of bandage, said follower being formed by bending the material upon itself to form an expandible member which extends from the top of the receptacle nearly to the bottom thereof to cause the follower and guard to bear upon the roll of bandage within the container.

HENRY W. ALLPORT.
